CASING FOR FLAT UMBRELLAS

Joachim Seidel, Solingen-Wald, Germany, assignor to Kortenbach & Rauh Kommanditgesellschaft, Solingen-
Weyer, Germany

Filed Aug. 22, 1969, Ser. No. 18,803

Term of patent 14 years

Int. Cl. D3—03

U.S. Cl. D87—1

FIG-1

FIG-4

FIG. 1 is an isometric top and side view of the casing according to the new design.

FIG. 2 is a view similar to that of FIG. 1, but showing the outer end face of the flap.

FIG. 3 is an isometric back and side view of the casing according to the new design.

FIG. 4 is a section taken along the line IV-IV of FIG. 3.

I claim:

The ornamental design for the casing for flat umbrellas, as shown.
